CLEANER FOR SWIMMING POOL FLOORS
Emil J. Drennan, 324 New Ave., Anaheim, Calif.
Filed Apr. 25, 1960, Ser. No. 24,359
1 Claim. (Cl. 15—1.7)

This invention relates to a cleaner for the floors of swimming pools, the same contemplating removal of dust, dirt and other accumulations by suction.

An object of the present invention is to provide a pool cleaner that applies its suction with a minimum of disturbance, thereby assuring efficient removal of dirt because of minimal scattering thereof during propulsion of the cleaner along a pool bottom.

Another object of the invention is to provide a pool cleaner vacuum head that has a low silhouette that causes minimum disturbance during movement along a pool floor and yet efficiently removes dirt within the area covered by the head during operative movement.

A further object of the invention is to provide a cleaner head of the character above referred to that is wheelborne, the wheels serving also as bumpers and are so proportioned as to extend above the low top of the vacuum head to create disturbances, if any, considerably above the head, thereby not affecting the smoothness or calmness of the water entering the head.

This invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description, and which is based on the accompanying drawing. However, said drawing merely shows, and the following description merely describes, preferred embodiments of the present invention, which are given by way of illustration or example only.

In the drawing, like reference characters designate similar parts in the several views.

FIG. 1 is a top plan view of vacuum cleaner for swimming pool floor, the same embodying a preferred form of the present invention.

FIG. 2 is an end elevational view thereof.

FIGS. 3, 4 and 5 are cross-sectional views as taken on the respective lines 3—3, 4—4 and 5—5 of FIG. 1.

FIG. 6 is a fragmentary longitudinal sectional view of a modification.

The present vacuum cleaner comprises, generally, a rectangular head 10, a set of traction wheels 11 on which said head is carried in spaced relation above the surface 12 of a swimming pool, means 13 partly enclosing the wheels 11 to minimize the disturbance that may be caused by said wheels as the same move over the pool surface 12, a suction outlet 14, to a hose 15, from the head 10, and a handle 16 for propelling the cleaner along the floor 12 and also serving as means to restore the head to a level position from a tilted position.

The head 10 is advantageously made of a heavy metal, of which brass is an example, thereby minimizing any tendency of the head to seek a tilted position, as when water beneath the head seeks to buoy up and tilt the same. In FIGS. 1 to 5, the head is shown as having a rectangular top plate 17 that, by means of front and back ribs 18, end ribs 19, and central ribs 20, defines an interior chamber 21 that has the centrally disposed outlet port 22 through the plate 17.

In the ribs 18, are provided elongated openings 23 which extend downwardly through the plate 17, the same being preferably located adjacent the ends of the plate in

2

symmetrical arrangement with relation to the outlet port 22. Beyond the ends 24 of the plate 17 there are provided loop-like extensions 25 that enclose elongated openings 26 similar to openings 23 except that the openings 23 are longitudinally arranged and the openings 26 transversely arranged.

The wheels 11 are so disposed and of such size that the same space the under surfaces of the ribs 18, 19 and 20 and extension 25 slightly above the pool floor 12, enabling the head 10 to move over said floor with minimum agitation of particles of dirt on the floor. The spaces between edges 18 and the floor are made to be less than the sum of the areas of openings 23 and 26. Thus, section effective in the outlet 22 sucks more water downward through said openings than is drawn past the peripheral edges of the head. The water from the openings 23 enters the restricted space beneath the ribs 18 and is drawn from said space into the chamber 21. Thus, there is a restriction beneath the ribs that imparts a particle-loosening force to the water that is quite effective to clean the pool floor 12 as the head is moved thereover on the wheels 11. This is true also of the water that enters the openings 26 in a downward direction, since this water is restricted by the ribs 19 and cleans beneath the ribs for the reasons above.

The wheels 11 are preferably made of soft rubber and are larger diametrically than the height of the head, therefore, extending substantially above the top surface of the head, as can be seen from the drawing. Said wheels have 30 axles 27 that are vertically adjustable in vertical slots 28 in hoods 29 that extend over the upper portions of the wheels and, while spaced therefrom, closely conform to the contour of the wheels. Said hoods comprise the means 13.

35 The axles 27 are above the top of the head 10, the latter, thereby, having the mentioned low-lying position and the top portions of the wheels and hoods substantially above the top of the head.

The wheels 11 are arranged, two on each end of the 40 head with the wheels at each end in tandem relation. Thus, the water-disturbing front of the wheel is reduced to an area presented by the front wheel at each end, depending, of course, on the direction the head is moved. In any case, the elevated portions of the wheels and 45 hoods are substantially above the top of the low-lying head so that the turbulence caused thereby is not effective on such flow that enters chamber 21 under the head.

It will be realized that the space between the head and 50 the pool floor may be regulated by suitable adjustment of the wheels. In any case, a space 30 is left between the wheels and the hoods 29 so that wheel-disturbed water is confined within these spaces.

The flow through outlet port 22 is received in the outlet 55 14 which is here shown as a swivel-mounted fitting 31 that is carried by bearing lugs 32 extending upwardly from the head 10 on both ends of outlet port 22. Trunnions 33 mount the fitting 31 in said lugs 32 on a longitudinal axis whereby said fitting is freely swingable from one side to the other of the head. Said fitting 31 is hollow and in the shape of a T, the same having an inlet port 34 that, in all positions of the fitting, is open to the outlet port 22. It will be realized that a flexible suction hose 15 on the end of said fitting will carry particle-laden water from the fitting to a place where the water may be filtered or otherwise cleaned and then returned to the pool.

Since the fitting 31 is freely swivelable on the trunnions 33, the same offers but little resistance to back and forth movement of the head in a cleaning operation since the same may flit to one side or the other accordingly. There may be instances when the head may seek

to tilt off a floor-engaging position. In such case, especially when the head tilts when being pulled rather than pushed, the handle 16 may be used to return the head to flat operating position.

The handle 16 is formed to have hooks 35 that engage over trunnions 33, which are elongated for that purpose, and abutment edges 36 that are adapted to engage the top face of the head plate 17. Since the handle stick 37 is arranged to extend at an upward angle from said abutment edges 36, it is a simple matter to bear down on said stick to cause said edges 36 to retilt the head back to operative position should the same become tilted, as above mentioned.

The handle 16 is removable from the head 10, the hooks 35 being shown with open slots 38 that allow separation of head and handle by first suitably swinging the handle to engage the hooks and then swinging the handle relative to the head to insure non-separable engagement until separation is desired.

The modification of FIG. 6 shows the head 10 with the chamber 21 omitted. This brings the entire under surface of the head plate 17a to the level of the lower surfaces of the ribs 18, 19 and 20. This arrangement also minimizes flow into the head from the front and rear edges, the same obtaining most of the flow from the 25 openings 23, as before described.

While the foregoing has illustrated and described what is now contemplated to be the best mode of carrying out the invention, the construction is, of course, subject to modification without departing from the spirit and scope 30 of the invention. Therefore, it is not desired to restrict the invention to the particular form of construction il-

lustrated and described, but to cover all modifications that may fall within the scope of the appended claim.

Having thus described this invention, what is claimed and desired to be secured by Letters Patent is:

A pool cleaner for cleaning surfaces of a pool beneath the surface of the water therein, comprising a rectangular head having down-reaching marginal ribs that define a bottom-open chamber, a set of wheels, two at each end of the head, supporting the head with the lower faces of said ribs in spaced proximity to the support surface, slots in the ribs, said head having an outlet from said chamber, a swivel-mounted fitting connected to a suction source, to draw water downwardly through said slots into the chamber to dislodge dirt particles on the support surface and to discharge said dirt-laden water outwardly of the head, trunnions provided to mount the swivel fitting, a handle separably connected to said trunnions to move the head along said surface, and said handle being provided with a non-tilting abutment to engage the top surface of the head.
